UNITED STATES PATENT OFFICE.

KONRAD DELBRÜCK AND KURT MEISENBURG, OF ELBERFELD, GERMANY, ASSIGNEES
TO FARBENFABRIKEN VORM. FRIEDR. BAYER & CO., OF ELBERFELD, GERMANY, A
CORPORATION OF GERMANY.

PROCESS OF PRODUCING 1,3-BUTYLENEGLYCOL.

1,094,539.

Specification of Letters Patent. Patented Apr. 28, 1914.

No Drawing.

Application filed January 21, 1913. Serial No. 743,318.

To all whom it may concern:

Be it known that we, KONRAD DELBRÜCK and KURT MEISENBURG, citizens of the German Empire, residing at Elberfeld, Germany, have invented new and useful Improvements in Processes of Producing 1,3-Butylene-glycol, of which the following is a specification.

It is a wellknown fact that acetaldehyde can be condensed in aqueous solution to aldol and that aldol can be reduced with sodium or with aluminium amalgam to 1,3-Butylene-glycol. In British Letters Patent No. 17259/11 a combination of the two processes is described consisting in reducing with metal amalgams, the crude aldehyde condensation product containing the aldol.

It has now been found that the reduction of the crude aldol product, obtained by condensation of an aqueous solution of acetaldehyde *e. g.* with potash, can be carried out advantageously by electrolysis. This new discovery was surprising, as combinations of the type

e. g. diacetone-alcohol are very sensitive to acids or alkalis and as the electrolytical reduction is effected in an acid solution. Another advantage of the new process is, that unchanged acetaldehyde or para-aldehyde is recovered by reduction as alcohol which then can be again oxidized to acetaldehyde.

In order to illustrate the new process more fully the following example is given, the parts being by weight:—100 parts of acetaldehyde are slowly mixed while being cooled with ice with 40 parts of cold water. A solution of 2.5 parts of potash in 25 parts of water is then added at a temperature of

10° C. This solution is after having been stirred at 10° C. for 14 hours, acidulated with sulfuric acid (25 per cent.) and finally made up with this acid to .750 parts. It is then reduced electrolytically for 24 hours in 45 the cathode part of a closed cell, neutralized with chalk, and the calcium sulfate is removed by filtration. The 1,3-butylene-glycol is obtained from the filtrate by fractionated distillation. The yield of glycol is more 50 than 50 per cent. of the acetaldehyde, and more than 30 per cent. of the aldehyde are recovered as alcohol.

We claim:—

1. Process for the production of 1,3-buty- 55 lene-glycol, which process comprises reducing aldol by electrolysis and separating the 1,3-butylene-glycol from the reaction mixture, substantially as described.

2. The process of producing 1,3-glycol 60 (1,3-diol) which comprises the electrolytic reduction of aldol in acid media.

3. The process of producing 1,3-glycol (1,3-diols) which comprises the electrolytic 65 reduction of aldols in dilute sulfuric acid solutions.

4. The described process of producing 1,3-glycol which consists in electrolytically reducing aldol in a dilute sulfuric acid solution, neutralizing the cathode liquid, and 70 separating therefrom the glycol.

In testimony whereof we have hereunto set our hands in the presence of two subscribing witnesses.

KONRAD DELBRÜCK. [L. S.]
KURT MEISENBURG. [L. S.]

Witnesses:

ALBERT NUFER,
MARGARET JOHNSON.

Correction in Letters Patent No. 1,094,539.

It is hereby certified that in Letters Patent No. 1,094,539, granted April 28, 1914, upon the application of Konrad Delbrück and Kurt Meisenburg, of Elberfeld, Germany, for an improvement in "Processes of Producing 1,3-Butyneglycol," an error appears in the printed specification requiring correction as follows: Line 25, formula, for "R₂CHOH-CH₂-COH" read R₂CHOH-CH₂-COR; and that the said Letters Patent be read with this correction therein that the same may conform to the record of the case in the Patent Office.

Signed and sealed this 23rd day of June, A. D., 1914.

[SEAL.]

R. F. WHITEHEAD,

Acting Commissioner of Patents.
